STORAGE BATTERY VENTING TUBE

Royal Watson, Sr., Shreveport, La.

Application June 14, 1956, Serial No. 41,899

Term of patent 14 years

(Cl. D26—6)

Fig. 1

Fig. 3

Fig. 4

Fig. 5

Fig. 2

Fig. 6

Fig. 1 is a perspective view of a storage battery venting tube, showing my new design;

Fig. 2 is a side elevational view thereof, partly broken away and in section;

Fig. 3 is a top plan view thereof;

Fig. 4 is a cross-sectional view thereof taken on line 4—4 in Fig. 2;

Fig. 5 is a cross-sectional view thereof taken on line 5—5 in Fig. 2; and

Fig. 6 is a bottom plan view thereof.

Portions of the drawing figures are diagonally lined to indicate transparency.

I claim:

The ornamental design for a storage battery venting tube, as shown and described.
